UNITED STATES PATENT OFFICE.

MAX F. MANGELSDORFF, OF UNION HILL, NEW JERSEY.

DRYING-MACHINE.

1,355,238.

Specification of Letters Patent. Patented Oct. 12, 1920.

Application filed September 14, 1918. Serial No. 254,061.

To all whom it may concern:

Be it known that I, MAX F. MANGELSDORFF, a citizen of the United States, residing in Union Hill, county of Hudson, and 5 State of New Jersey, have invented certain new and useful Improvements in Drying-Machines, of which the following is a full, clear, and exact specification.

My invention relates to drying machines 10 and refers particularly to machines adapted to the drying of products liable to adhere to each other.

One object of my invention is a device in which the products are intermittently inter- 15 mingling during the drying process.

Another object of my invention is a device in which the drying material is allowed to fall from one tray to another in the direction of the incoming drying air.

20 Another object of my invention is a device designed to prevent the drying particles from adhering to each other during the drying process.

Another object of my invention is a device 25 in which the material to be dried is spread in a practically uniform layer over each drying tray.

Another object of my invention is a device 30 in which the material to be dried is mixed and thoroughly submitted to the drying action of a flow of drying gas or air.

These and other objects of my invention 35 will be evident upon a consideration of my specification, drawings and claims.

My device is suitable for the drying of 40 any material particles, but is especially adapted for the drying of those materials, which have a tendency to adhere during the drying process, such as sliced vegetables, fruits, etc.

In order to prevent the above mentioned 45 adherence, it is essential that the particles be subjected to a gradual increase of heat, that there be an intermingling of the particles during the process and that the layers be of a uniform thickness of not too great a depth.

If the material be subjected at once to a 50 high heat, the particles will adhere due to their starchy or glutinous contents becoming dry while the various particles are in abutment with each other. It is evident therefore that the particle mass must be heated gradually while being subjected to sufficient

agitation to prevent their complete drying 55 while in an excessively wet condition. It is further evident that if the layers are too thick, or uneven, the weight of the material will cause the lower portions to adhere.

The device of my invention overcomes all 60 of these difficulties and presents a means whereby material of the described character may be completely dried without the adherence of the particles to each other.

In the accompanying drawings, illustrating one form of my device, similar parts are designated by similar numerals:

Figure 1 is a vertical cross-section of one form of my device.

Fig. 2 is a broken section through the line 70 2—2 of Fig. 1.

Fig. 3 is a section through the line 3—3 of Fig. 1.

Fig. 4 is a section through the line 4—4 of Fig. 5.

Fig. 5 is a section through the line 5—5 75 of Fig. 4.

Fig. 6 is a broken section through the line 6—6 of Fig. 1.

The particular form of my device shown 80 in the accompanying drawings comprises a drying box having the sides 20, 21, 22 and 23, the top 24 and the inclined bottom 25. The top 24 carries a hopper 26 at one end thereof and a centrally located stack 27. 85 Within the drying box are two series of spaced parallel trays A and B, each tray being composed of a series of revoluble plates, the axis of rotation of each series of plates being at right angles to the axis of 90 rotation of the revoluble plates of the adjacent tray. The hopper 26 contains a series of downwardly converging distributing plates 28, 28.

In the upper portion of the drying box, a 95 shaft 29 extends between the sides 20 and 22 and is revoluble therein. The shaft 29 carries the sprocket wheel 30 at each end thereof. Within the other side of the drying box and in alinement with the shaft 29 is the 100 shaft 31, revoluble within the sides 20 and 22, carrying a sprocket wheel 32 at each end thereof. The shaft 31 also carries the sprocket wheel 33. Meshing with the sprockets 30 and 32 is an endless chain 34, 105 carrying a series of extended distributing plates 35, 35. The sprocket 33 is connected to the sprocket 36, fixedly attached to the

revoluble shaft 37, by means of the chain belt 38. Revoluble upon the shaft 37 is a sprocket wheel 39, which is connected by the chain belt 40 with the sprocket idler 41 carried by the shaft 42. A miter gear 43' is integral with the sprocket 39 and meshes with the miter gear 43 revoluble upon the shaft 44. Integral with the miter gear 43 is the sprocket wheel 45, connected by means of the endless chain belt 46 with the sprocket wheel 48 fixedly attached to the revoluble shaft 49. The shaft 49 carries the fixedly attached gear wheel 50, meshing with the worm 51, which, in turn, is connected to a source of revoluble power. A revoluble shaft 52 carried by the walls 21 and 23, has the sprocket wheels 53 and 54 fixedly attached thereto. The sprocket 54 is connected to the sprocket 55 fixedly attached to the shaft 49 by means of the endless chain conveyer 56 having a series of outwardly extended partition plates 57, 57. The sprocket 53 is connected by means of a chain belt 58 to the sprocket 59 fixedly attached to the revoluble shaft 60, the shaft 60 carrying a series of fixedly attached outwardly extended discharging plates 61, 61.

The trays AA comprise a series of fominoous leaves 62, 62, preferably of wire gauze, fixedly attached to the revoluble shafts 63, 63, and the trays BB comprise a series of leaves 64, 64 fixedly attached to the revoluble shafts 65, 65. Each shaft 63 of a tray A is fixedly attached to a crank arm 66, the series of crank arms 66, 66 being pivotally attached to the connecting arm 67 at 68, 68. Each shaft 65 of a tray B is fixedly attached to a crank arm 69, the series of crank arms 69, 69 being pivotally attached to the connecting arm 70 at 71, 71. Each connecting arm 70 is pivotally connected at 72 to an arm 73 fixedly attached to the revoluble shaft 74 which also carries the gear wheel 75. Each connecting arm 67 is pivotally connected at 76 to the arm 77 fixedly attached to the revoluble shaft 78 which also carries the gear wheel 79. The chain belt 40 carries the gear racks 80, 80 capable of meshing with the gear wheels 79, 79 and giving them a half revolution. The chain belt 46 carries the two gear racks 81, 81 capable of meshing with the gear wheels 75, 75 and giving them a half revolution.

A pipe 82 connected with the drying chamber allows the introduction of hot air into the drying chamber, the air escaping through the stack 27.

The operation of the device is as follows:-

A revoluble movement is given the shaft 49 by means of the gear wheel 50 and the worm 51. The sprocket wheel 48, attached to the shaft 49, revolves the chain belt 46 with the racks 81, 81 over the sprocket wheel

45. During this movement of the chain belt 46, the racks 81, 81 mesh with the gear wheels 75, 75 giving them a semi-revolution, which, in turn, revolves the arms 73, 73, moving the connecting rods 70, 70, revolving the shafts 65, 65 by means of the crank arms 69, 69. Each movement of a shaft 65 causes the leaves 64, 64 to revolve first into an abutting position forming a tray B and then into parallel positions allowing the contents of a tray B to fall upon the tray A immediately beneath. The sprocket wheel 45 and the miter gear 43 revolve on the shaft 44, the miter gear 43 meshing with the miter gear 43' revolving the shaft 37, 80 over the idler sprocket 41. During this movement of the chain belt 40, the racks 80, 80 mesh with the gear wheels 79, 79, giving them a semi-revolution, which, in turn, revolves the arms 77, moving the connecting rods 67, 67, revolving the shafts 63, 63 by means of the crank arms 66, 66. Each movement of a shaft 63 causes the leaves 62, 62 to revolve first into an abutting position forming a tray A and then into parallel positions allowing the contents of a tray A to fall upon the tray B immediately beneath.

The racks 80, 80 and 81, 81 are so positioned that their movement will first revolve the lowest tray delivering the contents downwardly, then revolving the next tray above delivering its contents upon the empty tray beneath, this operation being repeated upwardly. The rapidity of the movement 100 of the chains 40 and 46, carrying the racks will time the rapidity of this delivering movement.

The revolution of the shaft 37 will revolve the sprocket 36, the chain 38, the 105 sprocket 33, the shaft 31, the sprocket 32 and thus move the chain 34 with the distributing plates 35, 35.

The revolution of the shaft 49, revolves the sprocket wheel 55, the conveyer chain 110 56, the sprocket wheel 54, the shaft 52, the sprocket wheel 53, the chain 58, the sprocket wheel 59, the shaft 60 and the discharging plates 61, 61.

From the above it will be seen that the 115 operation of the device, considering all the trays filled with material to be dried, is as follows:-

The leaves of the lowest tray are revolved discharging the contents upon the chain 120 conveyer which deposits them into the discharge chute 100, whence they are delivered by the delivering plates. The next to the bottom tray is then revolved and the contents deposited upon the lowest tray, this 125 operation being continuously repeated upwardly.

During the drying operation the material is introduced through the hopper 26 and distributed by the plates 28, 28 upon the 130

chain conveyer 34, which deposits it upon the upper tray, the plates 35, 35 spreading the material into practically a uniform layer.

Air of the requisite temperature is introduced through the pipe 82.

As the leaves of each tray are revoluble at right angles to those of the tray beneath, it is evident that the material will be thoroughly commingled and that the layers will be of approximate thickness.

I do not limit myself to the particular size, shape, number or arrangement of parts as described and shown, all of which may be varied without going beyond the scope of my invention as described and claimed.

What I claim is:—

1. In a drying machine, in combination, a drying box, a series of trays spaced vertically with respect to each other within the box, each tray comprising a series of elements capable of complete revolution, the series of revoluble elements of each tray being revoluble around axes at right angles to the axes of revoluble elements of the adjacent trays, automatic means for revolving the revoluble elements of each tray successively one-half revolution and means for passing a drying medium through the box.

2. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath and means for passing all of a drying medium through the foraminous plates.

3. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath, means for introducing material upon the upper tray, distributing members abuttable upon and movable over the material in the upper tray causing it to assume a practically uniform thickness of layer and means for passing all of a drying medium through the foraminous plates.

4. In a drying machine, in combination, a drying box, a series of trays spaced vertically with respect to each other within the

box, each tray comprising a series of elements capable of complete revolution, a revoluble axle to which each revoluble element is fixedly attached, the series of axles of each tray being at right angles to the series of axles of the adjacent trays, automatic means whereby the axles of each tray may be revolved a half revolution simultaneously, means whereby the axles of the series of trays may be revolved in sequence and means for passing a drying medium through the box.

5. In a drying machine, in combination, a drying box, a series of trays spaced vertically with respect to each other within the box, each tray comprising a series of elements capable of complete revolution, a revoluble axle to which each revoluble element is fixedly attached, the series of axles of each tray being at right angles to the series of axles of the adjacent trays, automatic means whereby the axles of each tray may be revolved a half revolution simultaneously, means whereby the axles of the series of trays may be revolved in sequence, means for introducing material upon the upper tray, distributing members abuttable upon and movable over the material in the upper tray causing it to assume a practically uniform thickness of layer and means for passing all of a drying medium through the foraminous plates.

6. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath, means whereby the material deposited by the lowest tray will be automatically removed from within the box and means for passing all of a drying medium through the foraminous plates.

7. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath, means for introducing material upon the upper tray, distributing members abuttable upon and movable over the material in the upper tray

causing it to assume a practically uniform thickness of layer and means for passing all of a drying medium through the foraminous plates.

8. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath, means for introducing material upon the upper tray, distributing members abuttable upon and movable over the material in the upper tray causing it to assume a practically uniform thickness of layer, means whereby material deposited by the lowest tray will be automatically removed from within the box, means for preventing heated air within the box from escaping on account of the removal of the material and means for passing heated air through the box.

9. In a drying machine, in combination, a drying box, a series of trays spaced vertically with respect to each other within the box, each tray comprising a series of elements capable of complete revolution, the series of revoluble elements of each tray being revoluble around axes at right angles to the axes of revoluble elements of the adjacent trays, automatic means for revolving the revoluble elements of each tray successively one-half revolution, means for regulating the period of time between the revolutions of adjacent trays and means for passing a drying medium through the box.

10. In a drying machine, in combination, a drying box, a series of trays spaced vertically with respect to each other within the box, each tray comprising a series of foraminous plates capable of complete revolution,

the series of plates of each tray being revoluble around axes at right angles to the axes of revolution of the plates of the adjacent trays, automatic means for revolving the plates of each tray successively one-half revolution commencing with the bottom tray depositing the contents of each tray upon the tray beneath, means for regulating the period of time between the revolutions of adjacent trays, means for introducing material upon the upper tray, distributing members abuttable upon and movable over the material in the upper tray causing it to assume a practically uniform thickness of layer and means for passing all of a drying medium through the foraminous plates.

11. In a drying machine, in combination, a drying box, a series of trays spaced vertically with respect to each other within the box, each tray comprising a series of foraminous plates capable of complete revolution, the series of plates of each tray being revoluble around axes at right angles to the axes of revolution of the plates of the adjacent trays, means for revolving the plates of each tray successively one-half revolution commencing with the bottom tray depositing the contents of each tray upon the tray beneath, means for regulating the period of time between the revolutions of adjacent trays, means for introducing material upon the upper tray, distributing members abuttable upon and movable over the material in the upper tray causing it to assume a practically uniform thickness of layer, means whereby material deposited by the lowest tray will be automatically removed from within the box, means for preventing heated air within the box from escaping on account of the removal of the material and means for passing heated air through the box.

Signed at Albion, in the county of Orleans and State of New York, this 10 day of September, 1918.

MAX F. MANGELSDORFF.
